UNITED STATES PATENT OFFICE.

JOHN C. WILSON, OF BOSTON, MASSACHUSETTS, ASSIGNOR TO THE MUNICIPAL SIGNAL COMPANY, OF PORTSMOUTH, NEW HAMPSHIRE.

MUNICIPAL TELEGRAPH.

SPECIFICATION forming part of Letters Patent No. 380,779, dated April 10, 1883.

Application filed Ju'y 28, 1886. Serial No. 209,304. (No model.)

To all whom it may concern:

Be it known that I, JOHN C. WILSON, of Boston, county of Suffolk, and State of Massachusetts, have invented an Improvement in 5 Municipal Telegraphs, of which the following description, in connection with the accompanying drawings, is a specification, like letters on the drawings representing like parts.

My invention relates to a municipal telegraph apparatus by means of which communication is established between a main office or police-station and signal-boxes on the streets that are provided with appliances for enabling responsible citizens to transmit signals to the 15 main office, so as to summon police aid, when required, and also for enabling police officers or other authorized persons to transmit various telegraphic messages or to place themselves in telephonic communication with the 20 main office, if required.

Apparatus of this class previously devised by me and described in various prior patents and applications has been arranged to serve, also, like a watchman's detector, to indicate 25 whether or not the policeman is attending to his duty, this being effected by causing the policeman to send a patrol or "on-duty" signal from the boxes at stated times, the said signals being distinguished in some manner at 30 the receiving-station from the want-calls, or those that require some action to be taken immediately upon their receipt.

In another application, Serial No. 206,571, filed June 29, 1886, I have described a system 35 in which the patrol-signals may be dispensed with and only the want-calls transmitted, the signal-boxes in said system containing indicating-signals, preferably perceptible from the outside of the box, controlled by the attendant at the main office, and indicating to an officer upon arrival at a box whether or not he is wanted to place himself in communication with the main office. In the apparatus shown in that application the indicating-signals at 40 all the boxes on one circuit were operated simultaneously from the main office, so that the officer would perceive the signal at any box on the circuit, and might consequently neglect to visit all the boxes on his beat without danger of immediate detection.

The present invention provides for causing

the officer to visit all the boxes at the prescribed time, or for detecting whether or not he does visit any given box.

The invention is embodied in a system in 55 which the boxes are provided with indicating-signals, preferably perceptible from the outside of the box, without opening the same, the said signals being so constructed and co-operating with operating devices at the main office of such a character that any desired one of the signals may be set independently of the others, so that if there is reason to suppose that an officer neglects to visit any one box the signal may be set at that box, and if the 65 officer does not respond within the proper period of time he can be called to account for his neglect, and the knowledge of this fact will be a strong inducement to the officer to properly attend to his duty.

Various devices might be employed for operating the indicating-signals individually or at one box independently of the other, the operation being analogous to that of the well-known individual signals used to call different 75 stations on a telephone-circuit, and the invention is not limited to the specific construction shown, although the apparatus devised for this purpose in the present invention is believed to contain various novel features by which it 80 is especially adapted for the purpose intended and for working in conjunction with the circuit and apparatus employed for telegraphic and telephonic communication between the main office and the sub-stations or boxes on 85 the streets.

Figure 1 is a front elevation of a signal-box forming part of a municipal telegraph system embodying this invention, and Fig. 2 a diagram representing the circuit and instrument 90 therein.

The signal-box *a*, containing signal-transmitting mechanism for transmitting telegraphic messages, may be of usual construction, being substantially the same as shown in various 95 patents granted to me, the said transmitting mechanism being arranged to be operated by a key inserted in the key-hole *a'*, accessible when the box-door is closed, and employed by citizens for the purpose of summoning police aid at the box. The box is also shown as containing a multiple signal-transmitting de-

vice controlled by a pointer, a^2 , co-operating with a dial, a^3 , having different wants indicated thereon and arranged to transmit a special telegraphic signal to indicate what is wanted in connection with the signal representing the number of the box to show the station at which the want is to be supplied. These features are common to the application shown in various patents previously granted to me. The box also contains a telephone, T, for communicating with the attendant at the main office, as provided for in the systems previously patented by me.

The present invention consists, mainly, in providing each box with an indicating signal, preferably a visual signal, consisting of a target or annunciator-drop, b , shown as supported on an arm, b' , controlled by the armature c of an electro-magnet, c' , the arm b' being normally engaged to retain the target concealed by the said armature when the magnet c' is demagnetized.

The box-door a^4 and the inner plate, a^5 , that protects the mechanism of the box, are provided with sight-openings a^6 a^7 , through which the target b may be seen when dropped, and there will preferably be a background, a^8 , having a luminous or phosphorescent surface at the rear of the drop or target b , as described and claimed in my former application hereinbefore referred to. The magnet c' is placed in a normally-open branch of the main circuit controlled by a device having a step-by-step movement, and also by a circuit-controlling device or switch, shown as operated by an electro-magnet and polarized armature, which may also operate a bell, S, used in the box as an audible-signal-receiving instrument, as described in my former application.

The operation of the devices controlling the movement of the drops b in the various boxes may be best understood by referring to the diagram, Fig. 2, which shows the instruments at the main office and at one of the boxes and the circuit connecting the same.

The apparatus at the main office comprises a receiving-relay, r , controlling a local circuit containing a register, R , of usual construction, for receiving telegraphic messages, and also a pole-changing instrument, P , of usual construction, by which the connection of the terminals of the main battery B with the terminals 4 5 of the main line may be reversed in the usual manner, and also a switch or key, K , for breaking the circuit. From the terminal 4 at the pole-changer P the main line is continued, as shown at 6, to the boxes or out stations o , at which the line entering passes through the transmitting apparatus, consisting of the usual break-wheels, m m' , the former for transmitting the number of the box and the latter for transmitting the desired one of the special want-signals, as in other apparatus of this class previously in use, it being understood that there are several wheels m' , each having a different-shaped signaling-surface, and that any desired one of said wheels is

brought into circuit by the movement of the pointer a^2 , Fig. 1. From the transmitting devices m m' the circuit is continued, as shown at 7, to the actuating-magnet d of the step-by-step device that controls the operation of the indicating-signal b , and from the said magnet the circuit is continued, as at 8, to the magnet i of the polarized signaling-instrument, used in this case also as a switch or circuit-changer. From said magnet i the circuit is continued, as at 9, to the telephone T , from which it continues through the other boxes a to the apparatus at the main office, before mentioned.

The magnet c' of the indicating-instrument is in a branch, 12, from the main line 7 before it reaches the magnet d , the said branch 12 being continued to a contact-piece forming one member of a circuit-closer, the other member, i' , of which is movable and actuated by the armature of the magnet i , and is connected by wire 13 with the wire 9 beyond the magnet i . Thus, if the branch 12 13 is closed at i' , the current will divide between the magnet c' in one branch and the magnets d and i in the other branch, a sufficient amount passing through the magnet c' to energize the same and to release the drop b , which, preferably, in falling operates to open a normally-closed circuit-breaker, f , in the branch 12, leaving said branch open as long as the signal remains displayed. The normal polarity of the line-current is such as to retain the armature of the magnet i in position to open the branch 12 13 at i' and to close a similar circuit-controller, i'' , at the other side of the said magnet, the purpose of which will be hereinafter described, and it will be seen that it is only necessary to cause a current of the opposite polarity to pass through the magnet i in order to open the circuit at i'' and close the branch circuit at i' , and thus cause the drop b to fall. In order to enable the magnet i to be thus affected at any desired station, but unaffected at the other stations, the said magnet is provided with a shunt, 14 15, of low resistance that includes a circuit-controller, d d' , one member of which consists of a disk fixed on the shaft d^3 , that is provided with a ratchet, d^4 , arranged to be operated with a step-by-step movement of the armature of the magnet d in the well-known manner.

The main portion of the periphery of the wheel d' is arranged to maintain contact with the spring d^2 , closing the shunt 14 15 of the magnet i , so that the currents on the main line do not affect the said magnet; but each of the said wheels d' at the different boxes is provided with a notch, d^5 , that comes opposite the spring d^2 and opens the shunt 14 15 at the unison or common starting-point for the movement of the step-by-step devices of the different boxes. Each disk d' is also provided with a second notch, d^6 , at a different distance from the notch d^5 in each different box, so that the notch d^6 at any given box is brought opposite to the spring d^2 to open the shunt after a definite number, different for each box, of step movements of

the ratchet d^4 from the unison or common starting-point, the magnets i in the different boxes thus being brought into circuit one at a time. Thus, when desired to operate the signal b at 5 any station, the proper number of step movements is given to the ratchet d^4 by opening and closing the circuit, and thus affecting the magnets d in the usual manner, and at the end of said movements the notch d^4 will be brought 10 under the spring d^5 at the station in question, as shown in the drawings, but at no other station, and then by reversing the polarity of the current in the main circuit the armature of the magnet i at that station only is affected and 15 closes the branch 12 13, causing the drop b to fall, as before described. If it is desired to operate the indicating-signals at more than one box or station, they may be successively operated in this manner, the apparatus differing 20 from the usual individual signals in this particular—namely, that one or more of said signals may be operated, as desired.

The unison of the step-by-step devices is effected in the following manner: The normally-closed circuit-closer i^2 of the magnet i is in a shunt, 16 17 18, for the magnet d , which shunt also includes a circuit-controlling device, $e e'$, the member e of which is rotated by the ratchet d^4 and is so arranged that during the main 30 portion of its rotation the shunt 16 17 18 is open; but when the wheel e arrives at the unison point a projection, e^2 , thereof comes in contact with the spring e' , thus closing the shunt 16 17 18, so that any additional impulses that 35 may be applied to the line to bring up the step-by-step devices that may have lagged behind will have no effect on the magnet d of the instrument that has arrived at the unison point.

40 In practice it will generally be best to bring the instruments to the unison point after the drops b have been released at the desired boxes, and then have the apparatus, with the magnets d , shunted out of circuit.

45 In order to start the step-by-step devices from the unison point, it is necessary to break the shunts 16 17 18 around the magnets d , which is effected by the polarized instruments i , and for this purpose the said instruments i have to be in circuit at all the boxes when the 50 step-by-step instruments are at the unison point. This is effected by the second notch, d^6 , in the wheel d' , that controls the shunt 14 15 for the magnet i , the said notch coming into 55 position to open the said shunt around the magnet i at the same moment the circuit-closer $e e'$ closes the shunt for the magnet d . A wheel, f , and co-operating pen f' are included in the branch 12, said wheel being fixed 60 to the shaft carrying the wheels d' , e , and d^4 , and having a notch, f^2 , corresponding in position with the notch d^6 of the wheel d' , so that when the shunt 16 17 18 is closed by the projection e^2 at unison point the other shunt, 14 65 15, is opened by the notch d^6 of the wheel d' , the branch 12 will be opened by the notch f^2 of the wheel f , for purposes to be described.

When the instruments are again to be operated, the line-current will be reversed from the polarity by which the step-by-step instruments 70 are normally operated, thus changing the position of the armatures of the instruments i at all the boxes and opening at i^2 the shunt 16 17 18 for the magnet d , which will thus be energized and move the ratchet ahead one step, 75 which will be sufficient to break said shunt 16 17 18 at $e e'$, so that when the current is again reversed for the purpose of opening the branch 12 13 at i^2 the magnet d will still remain in circuit. When the armature of instrument i 80 is moved to open the shunt 16 17 18, it closes the shunt 12 13, and were it not for the branch being opened at f^2 the drops would fall. The drop b will be restored by hand by the officer upon arriving at the box, and when the drop 85 is found displayed the officer will understand that he is directed to open the box and communicate with the main office by means of the telephone; or, in cases where telephonic communication is not provided for, the drop or 90 indicating-signal may be understood as a direction for the officer to proceed to the main office.

Signals of this kind may be used both for discovering whether or not the officer is attending to his duty, and also for facilitating police operations when required. For instance, if there is reason to suppose that an officer neglects to visit any particular box so often as required, the signal may be set at that box 100 only to discover whether or not the officer will respond within a reasonable time; but if the attendant at the main office desires to communicate with the officer on some matter of importance the signals may be set at all the 105 boxes, so that the officer will respond from whichever box he may next come to.

I do not herein broadly claim a police-signal comprising a main office and several sub-stations or street boxes connected by a single 110 wire and visual indicating-signals when the same consists of signal-lights for the several boxes adapted to be observed by a passing officer, and a controlling device for each signal-light, and a circuit-controlling device located 115 at the main station for effecting the operation of the several signal-light-controlling devices, whereby any one of the said lights may be operated to the exclusion of the others; nor do I herein claim a police-signal system comprising 120 a main office and several sub-stations or boxes connected by a single wire, circuit-changing devices contained in the boxes for transmitting signals, a receiving-instrument at the main office for receiving special signals, 125 and visual indicating-instruments when the same consist of signal-lights, and a controlling device for each signal-light, and a circuit-controlling device at the main station for effecting the operation of the several signal-light-controlling devices, to thereby operate the said lights independently, whereby two independent systems of communication are effected 130 over one wire between the main station and

the several sub-stations—viz., a system of code signaling from the several sub-stations to the main station for aid, &c., and a system of signaling from the main station to the several sub-stations independently to call the attention of the passing officer; nor do I herein claim a police-signal system of the kind described having visual indicating-signals for the several boxes adapted to be set in their normal position by hand and to be released independently by electrically-controlled devices, whereby the said visual indicating-signals may be displayed one after another and retained displayed until moved back to their normal position by hand, as the same forms the subject-matter of another application, Serial No. 252,335, filed by me October 14, 1887, wherein I have shown some of the apparatus contained in the invention as especially adapted to change the appearance of a light.

I claim—

1. A series of stations and circuit connecting the same, and indicating-instruments at said stations included in normally-open branches of said circuit, combined with a normally-shunted electro-magnetic circuit-controlling device or switch governing the branch circuit of said indicating-instrument, and a step-by-step device controlling the shunt for said switch, whereby the said shunt is opened and the switch rendered operative at a definite position only of the step-by-step device, substantially as described.

2. The combination of a step-by-step device and actuating-magnet therefor, with a shunt for said actuating-magnet, and a circuit-closer therein governed by said step-by-step device and arranged to close the said shunt at a definite position of said step-by-step device, and an electro-magnetic circuit-controlling device or switch, also controlling the said shunt for the actuating-magnet of the step-by-step device, whereby said shunt may be opened and the step-by-step device again operated, substantially as described.

3. The combination of the step-by-step device and actuating-magnet therefor, with a shunt for the said actuating-magnet, and circuit-closer therein governed by the step-by-step device, arranged to close the said shunt when the step-by-step device arrives at the unison point, and an electro-magnetic circuit-controlling device or switch, also controlling

the said shunt for the actuating-magnet of the step-by-step device, and a shunt for the magnet of said circuit-controlling device controlled by the step-by-step device, substantially as and for the purpose set forth.

4. In a police-signal system, the combination, substantially as described, of a main station and several sub-stations and circuit connecting them, and visual indicating-instruments at the sub-stations, an electro-magnetic device responsive to the impulses different from that employed in the transmission of the signals for operating the visual indicating-instruments, and another electro-magnetic device controlled by the operator at the main office for including and thereby rendering operative the electro-magnetic device controlling the operation of the visual indicating-instruments, substantially as described.

5. In a police-signal system, the combination, substantially as described, of several sub-stations and a main station and circuit connecting them, said main station containing a signal-receiving instrument, a pole-changing key, and a signal-transmitting key, and the sub-stations containing the signal-transmitting device, a visual indicating-instrument responsive to the movement of the pole-changing key of the main station, and an electro-magnetic device responsive to the transmitting-key of the main station for rendering operative by means of said pole-changing key the variable indicating device of the several sub-stations independently, substantially as described.

6. In a municipal telegraph system, the combination of the actuating-magnet, the shunt therefor, and means controlled by the armature of said actuating-magnet for closing said shunt at unison point, thereby cutting itself out, with an electro-magnetic device responsive to the impulses different from that employed to effect the actuating-magnet for opening said shunt of the actuating-magnet that it may be again actuated, substantially as described.

In testimony whereof I have signed my name to this specification in the presence of two subscribing witnesses.

JOHN C. WILSON.
